UNITED STATES PATENT OFFICE.

SAMUEL FRANK WELCH, OF AURORA, ILLINOIS, ASSIGNOR TO THE WESTERN WHEELED SCRAPER COMPANY, OF AURORA, ILLINOIS, A CORPORATION OF ILLINOIS.

MACHINE FOR HANDLING STONE, &c.

SPECIFICATION forming part of Letters Patent No. 699,266, dated May 6, 1902.

Application filed February 9, 1897. Serial No. 622,711. (No model.)

To all whom it may concern:

Be it known that I, SAMUEL FRANK WELCH, a citizen of the United States, residing at Aurora, in the county of Kane and State of Illinois, have invented certain new and useful Improvements in Machines for Handling Stone, Gravel, &c., of which the following is a specification, reference being had to the accompanying drawings, in which—

10 Figure 1 is a side elevation, part being broken away. Fig. 2 is an enlarged detail showing the mechanism through which the feed-conveyer is driven. Fig. 3 is a section on line 3 3 of Fig. 2. Fig. 4 is an enlarged detail of a part of the feed-conveyer, being substantially a cross-section on line 4 4 of Fig. 1. Fig. 5 is a plan view of a part of the feed-conveyer. Fig. 6 is a partial side elevation of the elevator. Fig. 7 is a cross-section 20 on line 7 7 of Fig. 6.

In preparing stone, gravel, &c., for use in making and repairing roads for ballast and kindred purposes it is frequently, if not always, necessary to run the material to be used 25 through a crusher to reduce it to the proper size, and in practice it is usual to arrange the crusher conveniently to the source of supply of such material, such as the quarry or gravel-pit. The stone or gravel may then be delivered to the crusher with more or less facility, and after it has been reduced to the desired size it is conducted by a suitable conveyer or elevator from the crusher to wagons or cars suitably placed to receive it.

35 While the apparatus above described is quite efficient in many respects, nevertheless a comparatively large force has been required to operate it, as the supply of material near the crusher being soon consumed it is 40 frequently necessary to move the apparatus nearer the supply or failing to do so to carry the gravel or rock a greater or less distance to it, both of which operations are laborious and time-consuming, and consequently expensive.

The principal object of my present invention is to provide an improved apparatus of the above general description which will be so constructed as to require a minimum 50 amount of handling or moving, thereby avoiding the objections above pointed out and mak-

ing the machine more economical and efficient than constructions heretofore employed. I accomplish this object by providing the crusher with a feed-conveyer arranged to receive the material to be crushed at a distance from the crusher and to convey it to and discharge it into the hopper of the crusher, said feed-conveyer being also arranged to be adjusted laterally and vertically 55 without necessitating any adjustment of the crusher, the feed-conveyer and crusher being also arranged to be driven from a common source of power. By this construction the gravel or rock may be removed from all 60 sides of the crusher without moving the crusher from its original position, it being necessary to move it only when the material within easy reach of the feed-conveyer has been exhausted.

My invention further contemplates certain improvements in driving mechanism for driving the feed-conveyer and also improvements in the details of the conveyer, &c., as will be hereinafter fully set forth.

Referring to the drawings, 8 indicates the crusher, which may be of any approved pattern, preferably the form shown in my Patent No. 549,263.

9 indicates the hopper of the crusher; 10, 80 its discharge-spout; 11, its drive-shaft; 12, a sprocket-wheel thereon, and 13 a belt-wheel by which the crusher is operated from a suitable source of power.

14 indicates a scaffold which rises from a 85 base 15, which also carries the crusher, as shown in Fig. 1. The scaffold 14 is designed to support the elevator or delivery-conveyer 16 and the upper end of the feed-conveyer 17, as well as parts of the driving mechanism, as 90 shown in Fig. 1.

18 indicates braces, preferably two in number, which connect the elevator 16 to the scaffold 14. 19 indicates similar braces which connect said elevator to the crusher.

As shown in Figs. 1, 6, and 7, the elevator 16 consists of a suitable frame and link belts 20 21, carrying buckets 22, the link belts being supported upon sets of pulleys 23 24, respectively, mounted upon transverse shafts 25, as 100 shown in Fig. 7. The belts 20 21 pass around sprocket-wheels 26 at the upper end of the

elevator, as shown in Fig. 1, and are operated at the same rate of speed by the rotation of said sprocket-wheels through the instrumentality of a sprocket-wheel 27, which is mounted upon the same shaft. The latter sprocket-wheel is connected by a chain or belt 28 to one of several sprocket-wheels mounted upon a shaft 29, carried by the scaffold 14, said shaft being driven from the shaft 11 of the crusher by a chain 30, which passes around the sprocket-wheel 12 and a sprocket-wheel 31, mounted upon the shaft 29. As shown in Fig. 1, the discharge-spout of the crusher is arranged to deliver the crushed material to the buckets 22 at the lower end of the elevator 16, in which it is carried up and discharged into wagons, cars, or other suitable receptacles.

As shown in Fig. 1, the upper end of the feed-conveyer 17 is suspended over the hopper 9 of the crusher from a horizontal arm 32 of the scaffold and is arranged to discharge its load into the hopper. In order to properly direct the material into the hopper, a funnel 33 is provided, which is suspended from the conveyer-frame in such position as to receive all material from the conveyer and discharge it into the hopper 9.

For the purpose of permitting the lower end of the feed-conveyer to be swung laterally when desired it is pivotally secured at its upper end to a vertical shaft 34, journaled in bearings 35, secured to the arm 32, as shown in Fig. 2. A split collar 36, which is secured to side plates 37 38, extending from the conveyer-frame, embraces the shaft 34 and forms a bearing, which supports the conveyer and permits it to swing in a circular path.

The lower ends of the plates 37 38 are perforated and receive sleeves 39 40, respectively, which are connected to the side plates 41 42 of the feed-conveyer, as shown in Fig. 2, thus forming pivotal bearings for the upper end of the conveyer, permitting vertical adjustment of the lower end thereof.

43 indicates a drive-shaft for the feed-conveyer. This shaft is journaled in the upper portions of the side plates 41 42 and passes through the sleeves 39 40, so that vertical adjustment of the conveyer does not affect the position of the shaft 43 relatively to the shaft 34. The shaft 43 carries a sprocket-wheel 44 and a beveled gear 45, the latter being in mesh with a beveled gear 46, mounted upon the lower end of the shaft 34. The shaft 34 also has a beveled gear 47 at its upper end, which meshes with a beveled gear 48, mounted upon a horizontal shaft 49, carried by the arm 32 of the scaffold 14. The shaft 49 is driven from the shaft 29 by means of a sprocket-chain 50, which passes around one of the sprocket-wheels on the shaft 29, thence around guide-wheels 51 52, and around a sprocket-wheel 53, carried by the shaft 49.

65 By the construction described the shaft 43 may be driven from the crusher and the feed-conveyer may be adjusted vertically or

laterally without interfering with the driving-gear or stopping the machine.

As shown in Fig. 1, the feed-conveyer is 70 preferably supported at its lower end upon suitable standards 54, and the conveying device consists of a belt 55, carried by the conveyer-frame on suitable rollers 56, journaled in the sides thereof, as shown in Fig. 4, said 75 belt having on one surface a series of side plates 57 58, which are arranged near the opposite edges of the belt, as shown in Fig. 5. The plates 57 58 are connected in pairs, the plates of each pair being, however, disconnected from other pairs, but the several pairs of plates overlap successively or are "shingled," by which construction the flexibility 80 of the belt is fully retained and the material carried is prevented from spilling. 85

The side plates 57 58 are connected in pairs and to the belt by transversely-arranged U-shaped plates 59 60 and intermediate bars 61, each pair of plates 59 60 being oppositely arranged at opposite sides of an intermediate 90 bar 61, the latter bar being secured to the plates 59 60 and to the belt. The plates 59 60 and bar 61 serve as buckets to carry the material thrown upon the belt.

62 63 indicate guide-boards, which are arranged at opposite sides of the feed-conveyer near its lower end, as shown in Figs. 1 and 4, and serve as a hopper to direct the material thrown upon the conveyer onto the belt.

As shown in Fig. 1, the feed-conveyer frame is provided at its ends with rolls or pulleys 64, around which the belt 55 passes, and the belt is driven from the shaft 43 by means of a sprocket-chain 65, which passes around the wheel 44, and a wheel 66, mounted 105 upon the shaft 67, which carries the upper pulley 64, and therefore for reasons already pointed out the feed-conveyer may be adjusted as desired without interfering with its operation or requiring adjustment of the driving devices. 110

In practice the crusher is located conveniently to a supply of material, as gravel, which is then shoveled onto the lower part of the feed-conveyer and is by it conveyed through 115 the funnel 33 to the crusher, from thence passing to the elevator and thence to a wagon or car. When the supply of material immediately adjacent to the feed-conveyer has been exhausted, the conveyer is shifted to a 120 new position, and the work may thus be continued without moving the crusher or elevator until all the material has been removed from within an area proportional to the radius of operation of the feed-conveyer, when 125 the apparatus may be shifted to a new position and the work continued.

That which I claim as my invention, and desire to secure by Letters Patent, is—

1. The combination with supporting devices, of a feed-conveyer, the discharge end thereof being pivotally suspended from said supporting devices at a point beyond the conveyer proper in a manner to permit the re-

ceiving end of said conveyer to be adjusted vertically and laterally without affecting the discharge, and a funnel suspended from the conveyer-frame and adapted to receive the discharge from said conveyer, substantially as described.

2. The combination with supporting devices, of a feed-conveyer, the discharge end thereof being pivotally suspended upon independent vertical and horizontal axes from said supporting devices at a point beyond the conveyer proper, in a manner to permit the receiving end of said conveyer to be adjusted vertically and laterally without affecting the discharge end thereof, and a funnel suspended from the conveyer-frame and adapted to receive the discharge from said conveyer, substantially as described.

3. The combination with a feed-conveyer pivotally supported at its discharge end so as to be capable of swinging vertically and laterally, of a funnel pivotally suspended under said conveyer and adapted to receive the discharge therefrom, substantially as described.

4. The combination with a shaft 34, of a shaft 43 arranged at right angles with said shaft, beveled gears connecting said shafts, a conveyer-frame pivotally suspended from said shaft 34 and carrying said shaft 43 about

which it pivots, and means for driving said conveyer from the shaft 43, substantially as described.

5. A conveyer-belt having at each side a series of overlapping side plates, and **U**-35 shaped plates connecting opposite side plates together and means connecting said **U**-shaped plates to the belt, substantially as described.

6. A conveyer-belt having at each side a 40 series of side plates, and **U**-shaped plates connecting opposite side plates together and means connecting said **U**-shaped plates to the belt, substantially as described.

7. A conveyer-belt having at each side a 45 series of overlapping side plates, and a pair of oppositely-arranged **U**-shaped plates connecting each pair of opposite side plates together and means connecting said **U**-shaped plates to the belt, substantially as described. 50

8. A conveyer-belt having at each side a series of side plates, a pair of **U**-shaped plates connecting each pair of opposite side plates together, and an intermediate bar between each pair of **U**-shaped plates and connected 55 to the belt, substantially as described.
